UNITED STATES PATENT OFFICE.

JAMES McGINLEY, OF CHICAGO, ILLINOIS.

FLUSHING-VALVE.

SPECIFICATION forming part of Letters Patent No. 290,256, dated December 18, 1883.

Application filed February 12, 1883. (No model.)

To all whom it may concern:

Be it known that I, JAMES McGINLEY, a citizen of the United States of America, residing at Chicago, in the county of Cook and 5 State of Illinois, have invented a new and useful Improvement in Flushing-Valves, of which the following is a specification, to wit:

This invention relates to valves for the purpose of flushing water-closet bowls; and it consists in a pair of alternately-closing valves connected to a supply-pipe, a tank or reservoir, and a flushing-pipe, and operated by a system of levers connected with the closet-seat, substantially as will be hereinafter set forth, and pointed out in the claims.

In order to enable others skilled in the art to which my invention appertains to make and use the same, I will now proceed to describe its construction and operation, referring to the accompanying drawings, in which—

Figure 1 is a view partly in section of my device applied to a water-closet, and Fig. 2 is an enlarged detail of the devices for adjusting the operating-levers and their connections.

25 A represents the bowl of a water-closet, and A' the seat covering the same, which is on its underside provided with the usual cup-shaped casting, a, for the reception of the upper end of a rod, B, which extends downward a short 30 distance, and is pivoted at its lower end to a lever, C, fulcrumed in a supporting-standard, c, secured to the floor, and the other end of this lever is pivoted to the lower end of a rod, D, extending up above the seat A' to a suitable height, and pivoted to a lever, E, fulcrumed at one end to the wall, and at the other connected to a valve-rod, F, as represented in Fig. 1. This valve-rod extends downward into a small valve-cylinder, F', having its upper and lower ends enlarged to receive the valves, and provided with two oppositely-faced valve-seats, as shown. The upper enlarged end of this cylinder is closed by a cap, f, provided with a suitable stuffing-box, 40 through which passes the valve-rod F, and the lower end is secured by a suitable coupling to the flushing-pipe f', connecting with the closet-bowl. To the upper end of the valve-cylinder is connected the supply-pipe G, leading to the water-mains, and between the upper and lower valve-seats is connected the pipe G', leading to the flushing-tank G². The

lower end of the valve-rod F is provided at a suitable distance apart, with two oppositely-seating valves, g g', removably secured to the 55 rod, as shown in the drawings.

At any point upon the system of levers between the fulcrum of the lever C and the valve-cylinder F' is secured a weight, H, which tends to keep the upper or supply valve, g, normally closed and the lower or flushing valve, g', opened.

When the closet is used, the seat is slightly depressed, operating by the intermediate system of levers to lift the valve-rod, opening the 60 valve g and closing the valve g'. The water from the main then enters the cylinder F', and, passing through the pipe G', fills the flushing-tank G². When the pressure upon the seat is removed, the weight H draws down the 70 valve-rod, closing the valve g and opening the valve g', allowing the water in the tank to flow out and flush the bowl. It will be seen that the valve g is held closed by the weight H and the pressure of water from the supply-pipe, and cannot fail to be closely seated, and also that the same amount of water will always flow into the bowl for flushing purposes, and none can be wasted by holding down or weighting the seat. The tank and flushing- 75 pipe f' being always emptied after the closet is used, cannot freeze.

In order to compensate for any displacement or wear of the seat by long use, and to adjust one size to different closets, I also provide the upper end of the rod B with a screw-threaded hole, b, into which is screwed a lengthening-rod, b', which may be screwed in or out and held wherever desired by a lock-nut, b². It is also necessary, in some cases, to 80 set the bowl farther from or nearer to the wall by reason of the location of the floor-joist, and in order to provide for this variation I form the rod or lever C in two parts, one of which telescopes within the other, and is held wherever required by a set-screw, c', as seen in Fig. 2.

Having thus fully described my invention, what I claim as new, and desire to secure by Letters Patent, is—

1. In a water-closet having its flushing devices operated by pressure upon the seat, a push-rod, B, provided with the screw-extension b' and lock-nut b², whereby it may be eas-

ily adjusted for different heights of seats and wear in use, substantially as and for the purpose set forth.

2. In a water-closet having flushing devices 5 operated by a push-rod and levers from the seat, the lever C, made in two parts telescoped together and secured by a thumb-screw, whereby it may be adjusted to the distance between the closet seat or bowl and the 10 flushing-valve, substantially as and for the purpose set forth.

3. In a water-closet, the hinged seat A', push-rod B, lever C, rod D, lever E, and valve-

rod F, provided with two valves adapted to open and close the supply and flushing pipes 15 alternately, the cylinder F', supply-pipe G, tank G², and flushing-pipe f', all combined, constructed, and arranged to operate substantially as and for the purpose set forth.

In testimony whereof I affix my signature in 20 presence of two witnesses.

JAMES McGINLEY.
